Fig. 4

UNITED STATES PATENT OFFICE.

GEORGE T. PEARSONS, OF NEW YORK, N. Y.

FIRE EXTINGUISHER.

Application filed April 11, 1918. Serial No. 227,857.

To all whom it may concern:

Be it known that I, GEORGE T. PEARSONS, a citizen of the United States, residing in the borough of Manhattan, in the city, county, and State of New York, have invented new and useful Improvements in Fire Extinguishers, of which the following is a specification.

This invention relates to fire extinguishers in which fire extinguishing liquid contained in a reservoir is discharged under a gas pressure generated in the reservoir, and it is an object of the invention to provide an improved gas generator to normally hold gas generating materials in a separated condition in the reservoir, said materials being permitted to unite by the removal of a closure for a receptacle included in the generator and containing one of the gas generating materials.

It is a further object of the invention to provide a generator comprising a chamber carrying a receptacle to contain a liquid gas generating material having an outlet with a removable closure with means arranged to carry a dry gas generating material in the generating chamber superposed to the liquid carrying receptacle in the upright position of the generator, and to permit the closure to move to a position to open the outlet of the liquid carrying receptacle and the liquid to flow from said receptacle to unite with the dry gas generating material when the generator is inverted.

It is a further object of the invention to provide improved closure means for the discharge outlet of the extinguisher, said closure being operable to automatically close the outlet in the upright position of the extinguisher and to move to position to open said outlet when the extinguisher is inverted, and operating to diffuse the liquid laterally as it is discharged from the reservoir.

It is another object of the invention to provide improved supporting means for the extinguisher whereby the extinguisher may have movement on an axis transverse to the longitudinal axis of the extinguisher, and the supporting means with the extinguisher to have movement on an axis transverse to the movement of the extinguisher in its support.

In the drawing accompanying and form-

ing a part of this specification, Figure 1 is 55 a longitudinal sectional view of a fire extinguisher showing an embodiment of my invention with the parts in normal inoperative position.

Figure 2 is a sectional detail plan view 60 of the outlet means for the reservoir taken on the line 2-2 of Figure 1.

Figure 3 is a detail plan view, taken on the line 3-3 of Figure 1 looking in the direction of the arrows, of means to extend 65 around the outlet and closure means for the carrier or receptacle for the liquid gas generating material in the generator; and

Figure 4 is a plan view of the supporting means for the extinguisher and showing the 70 extinguisher supported therein.

Similar characters of reference designate like parts throughout the different views of the drawing.

The embodiment of my invention shown 75 in the drawing comprises a reservoir 5 to contain fire extinguishing liquid, such as carbon-tetrachloride or a compound thereof, said reservoir having an opening at the top with a removable closure 6 for the insertion and removal of the generator and to refill the reservoir.

The reservoir has laterally projecting trunnions 7 to pivotally support the reservoir in a frame 8 to swing on an axis transversely of and at one side of the longitudinal axis of the reservoir. To allow the extinguisher to tip freely in all directions to maintain the extinguisher in equilibrium

as, for instance, on a ship, the extinguisher 90 is hung in this frame to have movement on a horizontal axis, and said frame is pivotally supported, in the present instance shown as suspended by trunnions 9 from

hangers 10 fixed to a ceiling, thereby permitting the supporting frame with the extinguisher to turn on an axis transversely to the movement of the extinguisher in the frame, and thus maintain the extinguisher in an upright position.

As shown the extinguisher is suspended by the hangers 10 and maintained in upright position by a chain or cable 11 attached at one end to the reservoir, as at 12, and passing over a pulley 13 with the other end secured in a suitable manner (not shown). The chain has a link 14 of a material which will fuse when the temperature rises to a predetermined

degree, the fusing of said link releasing the extinguisher, whereupon the extinguisher will automatically assume an inverted position due to the locating of the reservoir 5 trunnions 7 at one side of the longitudinal axis of the reservoir.

As stated it is an object of the invention to provide an improved gas generator to create or generate an expelling pressure for 10 the fire extinguishing liquid in the reservoir. This generator comprises a generator chamber formed of a tubular member 16 having an open end to constitute the top and at the closed end having a lateral annular 15 flange 17 with an outlet port or ports 18 at said end. A closure for said tubular member consists of a tubular shell 19 of greater length and diameter than the tubular member 16 and is adapted to engage or telescope 20 over the open end of said member 16 and to co-operate with the annular flange 17 to releasably connect the shell and tubular member 16 with a space between the side walls thereof, thus providing a closed chamber 25 or receptacle in which the gas is generated and from which it is led to the reservoir through the ports 18. Any suitable materials, one of which may be a liquid and the other a dry substance, such as sulphuric 30 or hydrochloric acid and bicarbonate of soda, coacting when combined or united to generate a gas, such as carbonic acid gas, may be utilized as the gas generating medium.

35 A receptacle or glass bottle 20 having an outlet to carry the liquid or acid is carried in the member 16, the outlet being closed by a removable closure in the form of a stopper 21 having a tapered part to engage 40 in the receptacle outlet in the normal upright position of the generator. A sleeve member 22 extends around the outlet of the receptacle and upward beyond the stopper 21 and having a spider 23 (Figure 2) at 45 the upper end with a stem 24 secured in or integral with the spider extending upward to adjacent the end of the closure 19. A disk 25 is mounted on the stem above the sleeve 22 to have longitudinal movement 50 to support the dry gas generating material or bicarbonate of soda in the member 16 superposed to the receptacle 20. This disk 25 is of slightly less diameter than the internal diameter of the tubular member 16. The 55 generator engages in an annular member 26 fastened to the bottom of the reservoir and is retained in position therein when the extinguisher is inverted by a rod 27 fixed at one end in a bridge 28 secured to or integral with the reservoir closure 6. In operation 60 as the extinguisher assumes an inverted position and therewith the generator the stopper 21 will move outward from the outlet of the receptacle 20 until it is arrested by 65 the spidered end of the sleeve 22, with the

part 21 of the stopper still engaging in the receptacle outlet providing a restricted outlet and thereby permit of the gradual flow of the acid from the receptacle, said acid flowing over the edges of the disk 25 and as 70 it unites with the bicarbonate of soda generating gas, the pressure of which gas in back of the disk or plate 25 will operate to move the disk along the stem 24 and eject the bicarbonate of soda from the member 16 into 75 the generator chamber, the generated gas passing out through the ports 18 into the reservoir. Means in the form of baffle plates 80 37 having minute perforations are arranged in the generating chamber interposed between the gas generating materials and outlet of the generator, and shown as arranged in the space between the member 16 and closure 19 and operate to prevent the entrainment of the gas generating materials with the generated 85 gas as it is discharged into the reservoir. It will be obvious that should the reservoir and therewith the generator be again moved to upright position that the stopper 21 would be guided to its seat and close the outlet of 90 the receptacle 20. By the provision of the sleeve member 22 any of the dry material which may pass through the space between the disk 25 and the wall of the member 16 will be lodged on the bottle 20 at the outside 95 of the sleeve member 22 and will be prevented by such sleeve from interfering with the opening movement of the stopper as the generator is inverted. It will be obvious that 100 in inverted position the sleeve engaging around the opening of the receptacle 20 in conjunction with the connected stem 24 engaging with the end of the closure 19 will maintain the receptacle at the closed end of the tubular member 16, but that the stopper 105 21 will have a limited movement outward away from the outlet of the receptacle 20. The discharge outlet of the reservoir is through a tubular member 30 threaded into the closure 6, said outlet normally being 110 closed in the upright position of the extinguisher by a closure in the form of a disk 31 seating on the end of a sleeve 32 threaded onto the member 30. To permit the closure 31 to have movement away from and toward 115 the end of the sleeve 32 and maintain the same in engagement with the end of said sleeve it is carried by a stem 33 projecting up from a perforated collar or spider 34 mounted in the sleeve 32 to have a limited 120 movement therein axially of the outlet between the end of the member 30 and an annular internal flange 35 of the sleeve 32. As the extinguisher assumes an inverted 125 position the closure will drop away from the end of the sleeve 32 and open the outlet through the member 30, sleeve 32 and openings on the spider 34, and this outlet may be varied by the adjustment of the sleeve to 130 permit the closure to have a greater or less

opening movement and thereby increasing or decreasing the outlet opening. The liquid as it is discharged will be diffused laterally by the closure and to facilitate such diffusion of the liquid the closure may be provided with a cone shaped portion 36. To make an air tight seal between the closure and discharge outlet the closure and its connection with the outlet sleeve 32 may be coated with 10 paraffin, this sealing being readily broken by the pressure of the liquid in the reservoir when the extinguisher is inverted and the gas generator is set in operation.

Having thus described my invention, I 15 claim:

1. In a fluid pressure generator for fire extinguishers, a generating chamber having an outlet with a tubular portion within the chamber; baffle plates interposed between 20 the wall of the tubular portion and chamber; an acid carrying receptacle in said tubular portion having an outlet; a stopper for the outlet of said receptacle; and means to carry a dry substance in the tubular portion 25 superposed to the liquid carrying receptacle and arranged with a stop to limit the outward movement of the stopper from the acid receptacle for the purpose specified.

2. In a gas generator for fire extinguishers, a closed receptacle having an outlet and a central tubular member extending up from the bottom with the walls spaced from the walls of the receptacle, a receptacle to 30 carry a liquid and having an outlet to engage in said tubular member; a stopper for the outlet of said receptacle; and means to carry a dry substance superposed to the liquid carrying receptacle in the upright position of the generator and arranged to 35 allow the stopper to have a limited outward movement from the outlet of the liquid carrying receptacle to permit the liquid to flow from the receptacle and unite with the dry substance when the generator is inverted.

3. In a gas generator for fire extinguishers, a generating chamber having an outlet; a receptacle in said chamber to carry a liquid gas generating material and having 40 an outlet; a stopper for the outlet of said receptacle; means to carry a dry gas generating material in the generating chamber superposed to the liquid carrying receptacle in the upright position of the generator and arranged with means to limit the outward movement of the stopper from the outlet of the liquid carrying receptacle to permit the liquid to flow from the receptacle and unite with the dry material when the generator is inverted; and means in the 45 generator to prevent the entrainment and discharge of the gas generating materials with the generated gas.

4. In a gas generator for fire extinguishers, an open end receptacle having an out-

let in and an annular flange at the closed end; a closure to telescope over the open end of the receptacle and spaced therefrom and co-operating with the flange of the receptacle to provide a closed receptacle; a second receptacle to carry a liquid gas generating material to engage in the first receptacle and having an outlet; a stopper for the outlet of said second receptacle; means to carry a dry gas generating material in the first receptacle superposed to the second receptacle in the upright position of the generator and arranged to allow the stopper to have a limited outward movement from the outlet of the second receptacle to permit the liquid to flow from said second receptacle and unite with the dry material when the generator is inverted; and a baffle arranged between the outlet of the first receptacle and the closure to prevent the entrainment and discharge of the gas generating materials with the generated gas.

5. In a gas generator for fire extinguishers, a tubular member open at one end; a second tubular member to engage over the open end of the first tubular member in spaced relation thereto to provide a closed chamber; an outlet from said chamber; a receptacle to carry a liquid gas generating material in said first tubular member; a stopper for the outlet of said receptacle; and means to carry a dry gas generating material in the first tubular member superposed to the liquid carrying receptacle 95 therein in the upright position of the generator and arranged with means to allow the stopper to have a limited movement outward from the outlet of the liquid carrying receptacle to permit the liquid to flow 100 from the receptacle and unite with the dry material when the generator is inverted, and operable by the generated gas to eject the superposed dry gas generating material from the tubular member for the purpose 110 specified.

6. In a gas generator for fire extinguishers, a generating chamber having an outlet and a tubular member therein open at the end opposite to the outlet; a receptacle to 115 carry a liquid gas generating material in said member; a stopper for the outlet of said receptacle; and means to carry a dry gas generating material in the tubular member superposed to the liquid carrying receptacle therein in the upright position of the generator and arranged to allow the stopper to have a limited outward movement from the outlet of the liquid carrying receptacle to permit the liquid to flow from the 120 receptacle and unite with the dry material when the generator is inverted, and operable by the generated gas to eject the superposed gas generating material from the tubular member; and means in the gener- 125 130

ating chamber to prevent the entrainment and discharge of the gas generating materials with the generated gas.

7. In a gas generator for fire extinguishers, a generating chamber having an outlet; a receptacle to carry a liquid gas generating material in said chamber having an outlet; a stopper for the receptacle outlet; a sleeve to extend around the receptacle outlet and 5 beyond the stopper arranged to permit of a limited outward movement of the stopper and having a stem extending to the end of the generating chamber; and means mounted on said stem to carry a dry gas generating 10 material superposed to the liquid carrying receptacle for the purpose specified.

8. In a gas generator for fire extinguishers, a generating chamber having an outlet; a receptacle to carry a liquid gas generating 20 material in said chamber having an outlet; a stopper for the receptacle outlet; a sleeve member to extend around the receptacle outlet and beyond the stopper and arranged to permit of a limited outward movement of 25 the stopper; having a stem extending to the end of the generating chamber; and means mounted on said stem and means to carry a dry gas generating material superposed to 30 said sleeve and the liquid receptacle as and for the purpose specified.

9. In a gas generator for fire extinguishers, a generating chamber having an outlet; a receptacle to carry a liquid gas generating material in said chamber having an outlet; 35 a stopper for the receptacle outlet; a sleeve member to extend around the receptacle outlet and beyond the stopper and arranged to permit of a limited outward movement of the stopper, said sleeve member having a 40 stem; and a disk movably mounted on said stem to carry a dry gas generating material superposed to the receptacle, for the purpose specified.

10. In a fluid pressure generator for fire 45 extinguishers, a generating chamber having an outlet with a tubular portion within the chamber; an acid carrying receptacle in said tubular portion having an outlet; a stopper for the outlet of said receptacle; means to

carry a dry substance in the tubular portion 50 superposed to the acid carrying receptacle and arranged to limit the outward movement of the stopper from the acid receptacle, said acid and dry substance being adapted to generate gas when mixed; and baffles in the generating chamber to prevent the entrainment 55 of the acid and dry substance with the discharge of the generated gas.

11. In a fluid pressure generator for fire extinguishers, a generating chamber having 60 an outlet and arranged to normally carry gas generating materials in a separated condition, and baffles in the generating chamber to prevent the entrainment and discharge 65 of the gas generating materials with the generated gas.

12. In a fluid pressure generator for fire extinguishers, a generating chamber having an outlet; means arranged in the generating chamber to normally carry gas generating 70 materials in a separated condition in the upright position of said generator and permit said materials to mix and generate gas when inverted; and baffles interposed between said means and the outlet to prevent the entrainment 75 and discharge of the gas generating materials with the generated gas.

13. In a chemical gas generator for fire extinguishers, a generating chamber having 80 an outlet; means in said chamber to maintain gas generating materials in a separated condition in the upright position of the generator and to permit said materials to mix when the generator is inverted, and baffles 85 in the generator for the purpose specified.

14. In a chemical gas generator for fire extinguishers, a generating chamber having an outlet and arranged with an open end tubular member centrally thereof; a receptacle to carry gas generating material in said tubular member having an outlet; means to carry another gas generating material in the tubular member superposed to the receptacle 90 therein; and baffles arranged between said tubular member and the outlet for the purpose 95 specified.

GEO. T. PEARSONS.
